GAME BOARD

Robert A. Hadfield, Milwaukee, Wis.

Application May 10, 1955, Serial No. 35,904

Term of patent 3½ years

(Cl. D34—5)

Figure 1 is a plan view of a game board showing my new design with movable elements mounted thereon for playing a game. The lines in Figure 1 indicate color contrast rather than any specific color.

Figure 2 is a side view of the game board.

Figure 3 is a detail section taken on line 3—3 of Figure 1, to show the pivotal mounting of the movable elements.

I claim:

The ornamental design for a game board, as shown and described.
